UNITED STATES PATENT OFFICE.

HENRY F. EASTMAN, OF CLEVELAND, OHIO.

DESIGN FOR AN AUTOMOBILE-CARRIAGE FRAME.

SPECIFICATION forming part of Design No. 35,305, dated November 19, 1901.

Application filed July 8, 1899. Serial No. 723,243. Term of patent 14 years.

To all whom it may concern:

Be it known that I, HENRY F. EASTMAN, a citizen of the United States, and a resident of Cleveland, county of Cuyahoga, State of 5 Ohio, have invented and produced a new and original Design for an Automobile-Carriage Frame, of which the following is a specification, reference being had to the accompanying drawings, forming part thereof.

10 In the accompanying drawings, Figure 1 is a side view of a motor-carriage frame, showing my new design. Fig. 2 is a plan view thereof. Fig. 3 is a rear elevation. Fig. 4 is a front elevation.

15 The leading or material feature of my design consists of the shape or configuration of the entire frame, as shown in the accompanying drawings.

The design consists of upper and lower and 20 connecting portions and a diagonal stem.

In the figures, 1 represents the bottom of the frame, which is transversely straight in the rear at 2. Thence the sides separate gradually in curved lines and finally in ogee curves 25 3 to join the inclined post 4, as seen in plan in Fig. 2. In side view in Fig. 1 the two sides of the bottom portion are seen to rise gradually toward the rear and in front to rise quickly in an ogee curve to form a "gooseneck" which enters the inclined stem 4.

The upper portion of the frame, as seen in plan in Fig. 2, is slightly wider in the rear than the bottom portion and is terminated in the rear by a straight transverse bar 5. The sides 30 separate gradually from the rear in curved

lines 6, being broadest at the front edge of the seat portion at 7. Thence the sides curve inwardly in a quick ogee 8 and unite at 9 in a single straight portion which joins the inclined stem 4. In side elevation, as seen in Fig. 1, the upper portion slopes gradually upward at 10 to the seat-lines 18, which are horizontal, thence downwardly in a forwardly-inclined line 12, and finally in an upward line 13, which is formed in an ogee curve and joins the inclined 45 stem at a point slightly above the lower portion.

The upper and lower portions of the frame are connected in the rear corners by outwardly-inclined and curved lines 14 and in 50 the front by a triangular formation of lines 15, connecting the two divisions of the bottom portion of the complete gooseneck and the upper line of the frame with the lower division at 16. In the side view, Fig. 1, the space 55 between the upper and lower lines of the gooseneck is divided into rectangular forms by the inclined lines of the connecting-bars at 16 and 17, only one bar being employed at 17.

Having described my invention, what I 60 claim as new, and desire to secure by Letters Patent, is—

The design for an automobile-carriage frame, substantially as shown and described.

Signed by me at Cleveland, Ohio, this 29th 65 day of June, 1899.

H. F. EASTMAN.
